UNITED STATES PATENT OFFICE

ELMER J. ZELT, OF FORT WAYNE, INDIANA, ASSIGNOR TO GENERAL ELECTRIC COMPANY, A CORPORATION OF NEW YORK

VARIABLE-VOLTAGE TRANSFORMER

Application filed October 17, 1928. Serial No. 313,106.

My invention relates to variable voltage transformers and more particularly to transformers having switching devices for varying or adjusting their voltages. The invention is especially useful in connection with small transformers such as are often used to operate electrical toys. Such transformers are generally supplied with current from a constant potential source but a secondary voltage which may be varied or adjusted between certain limits is often desirable. The general object of the invention is to provide a transformer with an improved switching arrangement for varying, or adjusting its voltage.

The invention will be better understood from the following description taken in connection with the accompanying drawing in which Fig. 1 is a perspective view of a transformer provided with a voltage adjusting switch constructed in accordance with the invention; Fig. 2 is a side view, partly in section, of the transformer shown in Fig. 1; Figs. 3 and 4 are views of details of construction, and Fig. 5 is a circuit diagram of the transformer windings and switch.

Like reference characters indicate similar parts in the different figures of the drawing.

The invention will be explained in connection with a transformer 10 enclosed in a sheet metal casing 11 as shown in Figs. 1 and 2 of the drawing. The transformer is provided with taps and tap leads extending to a tap switch mounted on one of the side walls 12 of the casing. A switch lever 13 is mounted outside the wall 12 of the casing to turn on a pin 14 carried by a plate 15 of insulating material which is secured against the inner surface of the wall 12. The pin 14 passes through a hole in the wall 12 somewhat larger than the pin so that the two do not touch.

The wall 12 has an opening 16 under the path of the outer or contact making end of the lever 13 so that this end of the lever may be moved by a knurled button 17 in a curved path along the outer surface of the plate 15.

The transformer has two windings 18 and 19 as indicated in Fig. 5. The winding 19 is divided into sections connected by tap leads 20 to fixed contacts 21 held in place by a

supporting strip 22 of insulating material. Lugs 23 extending from the edge of the opening 16 engage the notches 24 in the plate 15 and contact support 22 and are bent against the back of the latter to hold both these parts 55 in position. Openings or perforations 25 in the plate 15 are spaced and positioned to register with the contacts 21 which extend at least partly through these openings as shown in Fig. 4. Thus the lever 13 may make contact with any one of the contacts 21 when moved over it.

The winding 19, tap leads 20 and fixed contacts 21 are all formed from a single continuous conductor. After each section of this 60 winding is formed, a loop is left in the conductor before beginning the next section of the winding, the loops being long enough to form the tap leads 20 and fixed contacts 21, the ends of the loops being bent around the 65 contact support 22 to form the contacts 21 as shown most clearly in Fig. 4. The contact support has notches in its edges to receive the loops and maintain the contacts properly spaced. The insulation, if any, must be removed from the faces of the contacts which are exposed through the openings 25 in the plate 15 so that good electrical connection may be made between the contacts and the lever 13. The pin 14 and one end of the winding 19 are connected to the two outside transformer leads 26. It will be obvious that the 70 number of active turns in the winding 19 and therefore the voltage ratio of the transformer may be varied or adjusted by changing the 75 contact making position of the lever 13. The invention provides a simple and inexpensive construction and avoids the necessity for joints between the contacts 21 and their winding 19 so that there can be no trouble from 80 loose connections.

The invention has been explained by describing and illustrating a preferred form thereof but it will be apparent that various changes may be made without departing 85 from the scope of the invention as defined in the appended claims.

What I claim as new and desire to secure by Letters Patent of the United States, is:

1. A variable voltage transformer having 100

a winding, a plurality of fixed contacts connected to said winding, an insulating plate, a switch member mounted on said plate and movable along one of its faces, and means at the other face of said plate for supporting said contacts in spaced relation, said plate being perforated to permit said switch member to move over said contacts.

2. A variable voltage transformer having a winding, a casing enclosing said transformer, an insulating plate secured to the inner surface of said casing, a movable switch member outside said casing, means mounted on said plate and extending through said casing to support said switch member, means at the inner surface of said plate for supporting a plurality of fixed contacts, and connections between said contacts and said winding, said plate and casing having openings to permit said switch member to move over said contacts.

3. A switch including an insulating support, a plurality of conductors surrounding said support at spaced intervals to form a row of fixed contacts, an insulating plate adjacent said support, said plate having openings spaced to correspond to the spacing of said contacts, said contacts extending from their support through said openings, and a contact movable over said fixed contacts and along the face of said plate opposite said support.

In witness whereof, I have hereunto set my hand this 15th day of October, 1927.
